UNITED STATES PATENT OFFICE.

ROGER B. McMULLEN, OF CHICAGO, ILLINOIS.

DESIGN FOR A FENCE-GATE.

SPECIFICATION forming part of Design No. 19,258, dated August 6, 1889.

Application filed May 21, 1889. Serial No. 311,596. Term of patent 7 years.

To all whom it may concern:

Be it known that I, ROGER B. McMULLEN, a citizen of the United States, residing at Chicago, Illinois, have invented and produced 5 a new and original Design for Fence-Gates, of which the following is a specification, reference being had to the accompanying drawings, forming part thereof.

A gate of my design has a T-frame with side 10 and end bars with rounded corners and an open-mesh interior in the form of conventional diamonds, except at the margins, where the openings are triangular. Associated with this main feature of my design is a subordinate 15 feature, comprising an ornamental finish for the top of the gate, consisting of scroll-work.

In the drawings, Figure 1 shows a single or narrow gate of my design, and Fig. 2 shows a 20 double-width gate of the same general design. Both of the figures show a part broken away.

In said drawings, A represents the T-frame, the head of the T giving the flat exterior *a*, and the web thereof (marked *a'*) projecting at right 25 angles thereto and forming an inner border for the frame. The end bars of the frame extend in vertical lines and the side bars in horizontal lines, and the junction of said lines describes

curves *A'* at the respective corners of the gate. The interior or body work comprises the wires 30 *C*, which are woven in zigzag lines between the top and bottom bars, so as to form the diamond-shaped openings *B* and the triangular openings *b* and the twists or weaves *c*, which add also to the appearance or finish of 35 the gate.

D is the scroll-work, which is used as a finish, and the whole of which is constructed in curved forms, each of the pieces *d* giving the effect of a separate piece and each comprising 40 a central portion in long curve and the end portions in short curves. The central figure of this scroll-work may be of the design shown—*i. e.*, with an oval central portion and end portions curved or turned in opposite directions. The central ring-like structure *E* and cap *e* also add to the finish or appearance of 45 the gate.

I claim—

The design for a gate, the same comprising 50 the design herein shown and described.

ROGER B. McMULLEN.
